UNITED STATES PATENT OFFICE.

LOTHAR VON GRAVE, OF WALLINGFORD, CONNECTICUT, ASSIGNOR TO THE
H. L. JUDD & COMPANY, OF NEW YORK, N. Y.

DESIGN FOR A PICTURE-FRAME.

SPECIFICATION forming part of Design No. 23,217, dated April 24, 1894.

Application filed March 27, 1894. Serial No. 505,345. Term of patent 3½ years.

To all whom it may concern:

Be it known that I, LOTHAR VON GRAVE, a subject of the King of Prussia, residing at Wallingford, Connecticut, have invented and produced a new and original Design for Picture-Frames, of which the following is a specification, reference being had to the accompanying drawing, wherein the figure shows a face view of a frame illustrating my design, 10 one-half only of said view being shown in full lines, the other half being shown in outline.

The essential features of my design consist in an inner elliptical portion, surrounded by an open-work, leaf-like portion, with chasing 15 thereon, and following the general contour of the inner elliptical portion and with leaf-like projections extending therefrom at the top and bottom of the frame.

In the drawing, *a* designates an inner elliptical ornamental portion provided with an opening *b*. Surrounding this inner elliptical portion is an openwork leaf-like portion *c* having chasing *d* thereon and following the general contour of the inner elliptical portion *a*, and with leaf-like projections *e* extending from the bottom and top of the frame. 20 25

What I claim is—

The design for a picture frame, substantially as shown and described.

LOTHAR VON GRAVE.
